REFRIGERATION

Application filed March 7, 1932. Serial No. 597,161.

My invention relates to the art of refrigeration and particularly to refrigeration by what is commonly termed the flash method.

In refrigerating apparatus employing the flash method, a liquid to be refrigerated, usually water or a brine solution, is introduced into a receptacle or flash chamber wherein a high degree of vacuum (low absolute pressure) is maintained. A portion of the liquid is evaporated due to the low pressure and the heat of evaporation is taken from the remaining liquid, thereby cooling it.

I prefer to maintain the vacuum in the flash chamber by means of a steam ejector or thermo-compressor. A thermo-compressor utilizes steam under pressure and emitted at high velocity into a converging tube to draw vapor from the flash chamber, thus producing a vacuum in the latter. The thermo-compressor discharges into a condenser where the steam used to operate the thermo-compressor and the vapor withdrawn from the flash chamber are condensed.

In a refrigerating apparatus of this type the temperature to which the liquid in the flash chamber is cooled by evaporation bears a direct relationship to the degree of vacuum maintained in the flash chamber.

Hence, in order to regulate the temperature of the liquid it is necessary to regulate the vacuum maintained. This may be done by varying the quantity of steam supplied to the thermo-compressor, but I have found that close regulation is not obtainable in this manner. Due to the inherent characteristics of thermo-compressors, a wide variation over one range in the amount of steam supplied thereto may have but little effect on the vacuum produced, while a small variation over another range may have a large effect on the vacuum. In accordance with my invention, I regulate the vacuum produced by reintroducing a portion of the vapor withdrawn

from the flash chamber. To do this I provide a conduit connecting the outlet of the thermo-compressor with the flash chamber. As a higher absolute pressure exists at the outlet of the thermo-compressor than in the flash chamber, vapor may pass through the above

connection and will increase the absolute pressure in the flash chamber. In order to regulate this pressure, I provide a valve in the conduit connecting the flash chamber with the outlet of the thermo-compressor. This valve is preferably automatically regulated in accordance with either the pressure existing in the flash chamber or in accordance with the temperature therein or in accordance with the temperature at some other point in the system.

My invention will be more fully described in the following description considered in connection with the accompanying drawing which forms a part of this specification and which is a more or less diagrammatic view, chiefly in cross-section, of a preferred embodiment of my invention.

Referring to the drawing, reference character 10 designates a closed vessel, hereinafter termed a flash chamber. Liquid to be cooled, for instance, water, is introduced into chamber 10 by means of a conduit 11, adjacent to the open end of which is a distributing member 12. Member 12 serves to break up and spread the stream of liquid discharged from conduit 11. A conduit 13 is connected to the bottom of flash chamber 10 and to the intake of a pump 14. Pump 14 discharges through a conduit 15.

In the embodiment shown, the refrigerating system is used in connection with an air conditioning system, although my invention is in no way limited to such an application. Air to be conditioned is introduced into a chamber 16 through a conduit 17 and is discharged therefrom through a conduit 18. In the upper part of chamber 16 there is located a distributor or spraying means 19. Conduit 15 is connected to distributor 19 and supplies cold liquid thereto. Conduit 11 is connected to the bottom of chamber 16.

A thermo-compressor 20 is provided with an inlet opening 21 and an outlet opening 22. Inlet opening 21 is connected to flash chamber 10. Thermo-compressor 20 comprises a series of nozzles 23 connected to a steam chest 24 which is supplied with steam under pressure through a conduit 25. Nozzles 23 discharge into a converging tube 26 which is connected

to a diverging tube 27. The outlet 22 of the thermo-compressor is connected to a condenser 28.

Condenser 28, in the embodiment shown, 5 is of the direct contact type wherein cooling water introduced through a conduit 29 is sprayed by means of a distributor 30 in direct contact with the steam discharged into the condenser from the thermo-compressor. The 10 mixture of cooling water and condensate is withdrawn by means of a pump 31 through a conduit 32 and is discharged through a conduit 33. A barometric condenser and steam jet air pump 34 are connected to the upper 15 part of condenser 28.

A conduit 35 connects the outlet 22 of the thermo-compressor with flash chamber 10. A valve 36 is located in conduit 35 and serves to control the flow of fluid therethrough. 20 Valve 36 is shown to be of an automatic type and comprises a valve member 37 mounted on a stem 38, the other end of which is secured to a piston 39. Piston 39 is reciprocably mounted in a cylinder 40. A spring 41 is 25 disposed between cylinder 40 and piston 39 and tends to maintain the valve in open position. Means may be provided as indicated at 60 for varying the tension of spring 41. A conduit 42 is connected to the lower end of 30 cylinder 40 and to a thermostat bulb 43. Bulb 43 is shown as being located in a well 44 in the lower part of flash chamber 10. Bulb 43, conduit 42 and cylinder 40 below piston 39 are filled with a fluid which 35 expands upon a rise in temperature and contracts upon a decrease in temperature. The illustration with respect to this valve is to be considered a diagrammatic illustration, it being understood that various types of automatic temperature controlled valves are 40 known which can be used in this connection.

The operation of the above described apparatus is as follows:

45 Steam is supplied under pressure through conduit 25 to steam chest 24 and is discharged with a high velocity through nozzles 23 into converging tube 26. As is well known, this produces a vacuum in the neighborhood of 50 the ends of the nozzles and, inasmuch as this region is in communication with flash chamber 10, a vacuum is produced in the flash chamber. This vacuum causes liquid to be 55 drawn through conduit 11 from the bottom of chamber 16 and this liquid is discharged into flash chamber 10. The stream of liquid introduced into flash chamber 10 is broken up by means of member 12. Due to the 60 vacuum maintained in flash chamber 10 a portion of the liquid is evaporated and the heat necessary for this evaporation is supplied by the remaining liquid. Consequently, the temperature of the remaining liquid is reduced. 65 The liquid thus cooled is withdrawn from

the flash chamber through conduit 13 by pump 14 and is discharged through conduit 15 to distributor 19. In chamber 16 the cold liquid discharged from distributor 19 comes in intimate contact with air introduced through 70 conduit 17 and thus serves to cool the air and is itself heated. The air thus cooled is discharged through conduit 18.

The vapor withdrawn by the thermo-compressor from flash chamber 10 and the steam 75 discharged from nozzles 23 are mixed and pass through tubes 26 and 27 into condenser 28. In the condenser the vapors are brought into intimate contact with cooling water discharged through distributor 30 and are condensed. The cooling water and condensate mix and the mixture is withdrawn through conduit 32 by pump 31 and is discharged through conduit 33. A low pressure is maintained in condenser 28 due to the condensation of the vapors and due to the barometric condenser and steam jet air pump 34, which latter serves to remove noncondensable gases. 80

If valve 36 is open, a portion of the vapor discharged through outlet 22 passes through 90 conduit 35 to flash chamber 10. Hence, under these conditions, the thermo-compressor must again remove this reintroduced vapor. Therefore the thermo-compressor will not maintain as high a degree of vacuum in the 95 flash chamber as it would if valve 36 were closed.

It is evident that the amount of cooling 100 which must be carried out in flash chamber 10 is dependent upon the temperature of the air 100 to be cooled which is introduced through conduit 17 and/or on the temperature to which it is desired to cool this air. The latter condition is usually constant and hence if the 105 temperature of the air introduced through conduit 17 increases it is necessary to remove more heat therefrom. This will result in the temperature of the water introduced into flash chamber 10 becoming higher, whereupon a greater amount must be evaporated in order to reduce it to the desired 110 temperature. However, the thermo-compressor operates to withdraw vapor at a constant rate for a given pressure in the flash chamber and hence it is unable to withdraw 115 all of the increased amount of vapor. The result is that less vapor is withdrawn than that necessary to maintain the desired vacuum and hence the pressure rises. Inasmuch as the 120 temperature and pressure bear a direct relationship to each other, the temperature of the liquid in the lower part of the flash chamber rises slightly. However, this rise in temperature causes the fluid within element 43 to expand which in turn causes piston 39 to be raised against the action of spring 41 and to close, more or less, valve 36. The 125 result of the closing of valve 36 is that less vapor may pass through conduit 35 and hence the thermo-compressor has less vapor 130

to remove from this source and is therefore able to remove more vapor flashed in flash chamber 10, whereby the desired degree of vacuum is restored and hence the desired 5 temperature is maintained. Disregarding the slight fluctuations necessary to operate the valve, the result is that a substantially constant pressure is maintained in flash chamber 10 irrespective of the fact that evaporation takes place therein at an increased rate.

In the event that less cooling effect is required, the temperature of the water introduced into the flash chamber becomes lower and hence a smaller amount need be evaporated to remove the heat necessary to reduce the temperature to the desired point. However, the thermo-compressor removes vapor at a constant rate and therefore it removes more vapor than it should to reduce the temperature to said desired point. The result is that both the pressure and the temperature are temporarily reduced below their desired values, whereupon valve 36 opens and allows more vapor to pass through conduit 35. The thermo-compressor now has to remove this additional vapor and hence can remove less vapor flashed in the flash chamber. The result again is the maintenance of a substantially constant pressure, and hence 30 a substantially constant temperature, in flash chamber 10.

Instead of controlling valve 36 directly by the temperature of the water in the lower part of the flash chamber, the valve may be controlled directly in response to temperatures in other parts of the system. In the drawing there are illustrated wells located at various points. A well 50 is shown in the vapor space of flash chamber 10. A well 51 is shown in conduit 15. Wells 52 and 53 are shown in conduits 17 and 18, respectively, while a well 54 is shown in conduit 11. Thermostat element 43 may be located in any of these wells, whereupon valve 36 will be controlled directly in accordance with the temperature adjacent to the well in which element 43 is located. It will be appreciated that it may be necessary to change the tension of spring 41 for different locations of the element 43. Furthermore, the temperature to be maintained can be regulated by varying the tension of spring 41.

Inasmuch as the temperature and pressure existing in flash chamber 10 are directly proportionate to each other, the pressure may be used to operate piston 39 directly. For this purpose there is shown a conduit 55 provided with a manually operable valve 56 connected to the vapor space of flash chamber 10. In order to operate valve 36 directly in accordance with the pressure in the flash chamber, element 43 may be removed from conduit 42 and conduit 42 connected directly to conduit 55. Thus, the pressure existing in flash chamber 10 will be communicated to cylinder

40 below piston 39. Again, it may be necessary to alter the tension of spring 41 or use a spring of different strength in order that the desired pressure may be maintained in flash chamber 10.

Instead of utilizing valve 36 to maintain a constant pressure and temperature in the flash chamber, it is obvious that it may be used to vary the pressure and temperature maintained. Thus, if it is desired to reduce the pressure and temperature, the tension on spring 41 is decreased, whereupon valve 36 will be closed by a lower pressure acting on piston 39.

It will thus be noted that I have provided an extremely simple means for obtaining a very close regulation of the temperature and pressure existing within the flash chamber. The apparatus operates to maintain a substantially constant temperature and pressure, the only variation being that necessary to operate valve 36, and such variations are only temporary, inasmuch as the opening or closing of valve 36 causes the temperature and pressure to almost immediately return to the temperature and pressure at which it is desired to maintain the flash chamber.

It will be understood that my method of regulation is applicable to other fluids such as milk.

While I have shown and described one more or less specific embodiment of my invention, it is to be understood that this is for purposes of illustration only and that modifications fall within its scope. My invention may be used with other than air conditioning apparatus. It will be understood that the invention is to be limited only by the scope of the appended claims.

What I claim is:

1. The method of refrigeration which comprises introducing liquid into a closed vessel, withdrawing vaporous fluid from said vessel to maintain a vacuum therein, and reintroducing a portion of said vaporous fluid into said vessel to regulate the degree of vacuum maintained therein.

2. The method of refrigeration which comprises introducing liquid into a closed vessel, withdrawing vaporous fluid from said vessel to maintain a vacuum therein, reintroducing a portion of said vaporous fluid into said vessel, and controlling the amount of vaporous fluid reintroduced so as to maintain a substantially constant degree of vacuum in said vessel.

3. The method of refrigeration which comprises introducing liquid into a closed vessel, withdrawing vaporous fluid from said vessel to maintain a vacuum therein, reintroducing a portion of said vaporous fluid into said vessel, and controlling the amount of vaporous fluid reintroduced in accordance with the temperature of the fluid within said vessel

so as to maintain a substantially constant degree of vacuum therein.

4. The method of refrigeration which comprises introducing liquid into a closed vessel, withdrawing vaporous fluid from said vessel to maintain a vacuum therein, reintroducing a portion of said vaporous fluid into said vessel, and controlling the amount of vaporous fluid reintroduced in accordance with the pressure of the fluid within said vessel so as to maintain a substantially constant degree of vacuum therein.

5. The method of refrigeration which comprises introducing liquid into a closed vessel, withdrawing vaporous fluid from said vessel to maintain a vacuum therein, cooling the liquid in said vessel by evaporation due to the vacuum, withdrawing cooled liquid from said vessel, cooling air with said liquid, and reintroducing a portion of said vaporous fluid into said vessel to regulate the temperature to which said air is cooled.

6. The method of refrigeration which comprises introducing liquid into a closed vessel, withdrawing vaporous fluid from said vessel to maintain a vacuum therein, cooling the liquid in said vessel by evaporation due to the vacuum, withdrawing cooled liquid from said vessel, cooling air with said liquid, reintroducing a portion of said vaporous fluid into said vessel, and controlling the amount of vaporous fluid reintroduced so as to maintain substantially constant the temperature to which said air is cooled.

35 7. In a refrigerating apparatus, a flash chamber, means for introducing liquid into said flash chamber, means for withdrawing liquid from said flash chamber, means for withdrawing vapor from said flash chamber, and means for introducing vapor into said flash chamber.

45 8. In a refrigerating apparatus, a flash chamber, means for introducing liquid into said flash chamber, means for withdrawing liquid from said flash chamber, means for withdrawing vapor from said flash chamber, means for reintroducing withdrawn vapor into said flash chamber, and means controlling the amount of vapor reintroduced so as 50 to maintain a substantially constant pressure in said flash chamber.

55 9. In a refrigerating apparatus, a flash chamber, means for introducing liquid into said flash chamber, means for withdrawing liquid from said flash chamber, means for withdrawing vapor from said flash chamber, means for reintroducing withdrawn vapor into said flash chamber, and means responsive to the pressure in said flash chamber for controlling the amount of vapor reintroduced thereinto.

60 10. In a refrigerating apparatus, a flash chamber, means for introducing liquid into said flash chamber, means for withdrawing liquid from said flash chamber, means for

10 withdrawing vapor from said flash chamber, means for reintroducing withdrawn vapor into said flash chamber, and means responsive to the temperature in said flash chamber for controlling the amount of vapor reintroduced thereinto.

11. In a refrigerating apparatus, a flash chamber, means for introducing liquid into said flash chamber, means for withdrawing liquid from said flash chamber, a thermocompressor having an intake passageway and an outlet passageway, means connecting said inlet passageway with said flash chamber, a conduit connecting said outlet passageway with said flash chamber, and means for controlling flow through said conduit.

15 12. In a refrigerating apparatus, a flash chamber, means for introducing liquid into said flash chamber, means for withdrawing liquid from said flash chamber, a thermocompressor having an intake passageway and an outlet passageway, means connecting said inlet passageway with said flash chamber, a conduit connecting said outlet passageway with said flash chamber, a valve in said conduit, and means responsive to temperature within said flash chamber for controlling said valve.

20 13. In a refrigerating apparatus, a flash chamber, means for introducing liquid into said flash chamber, means for withdrawing liquid from said flash chamber, a thermocompressor having an intake passageway and an outlet passageway, means connecting said inlet passageway with said flash chamber, a conduit connecting said outlet passageway with said flash chamber, a valve in said conduit, and means responsive to pressure within said flash chamber for controlling said valve.

25 14. In a refrigerating apparatus, a flash chamber, means for introducing liquid into said flash chamber, means for withdrawing liquid from said flash chamber, a thermocompressor having an inlet passageway and an outlet passageway, means connecting said inlet passageway with said flash chamber, a condenser, means connecting said outlet passageway with said condenser, a conduit connecting said outlet passageway with said flash chamber, and means for controlling flow through said conduit.

30 15. In a refrigerating apparatus, a flash chamber, means for introducing liquid into said flash chamber, means for withdrawing liquid from said flash chamber, a thermocompressor having an inlet passageway and an outlet passageway, means connecting said inlet passageway with said flash chamber, a condenser, means connecting said outlet passageway with said condenser, a conduit connecting said outlet passageway with said flash chamber, a valve in said conduit, and means responsive to temperature within said flash chamber for controlling said valve.

35 16. In a refrigerating apparatus, a flash

chamber, means for introducing liquid into said flash chamber, means for withdrawing liquid from said flash chamber, a thermo-compressor having an inlet passageway and 5 an outlet passageway, means connecting said inlet passageway with said flash chamber, a condenser, means connecting said outlet passageway with said condenser, a conduit connecting said outlet passageway with said 10 flash chamber, a valve in said conduit, and means responsive to pressure within said flash chamber for controlling said valve.

17. Air conditioning apparatus comprising a spray chamber, means to supply air to 15 and withdraw air from the spray chamber, a flash vessel, means to conduct water from the flash vessel to the spray chamber, a thermo-compressor connected to withdraw vapor from the flash chamber, a condenser 20 connected to receive vapor from the thermo-compressor, a by-pass conduit for conducting vapor from the discharge side of the thermo-compressor back to the inlet side thereof, a valve in said by-pass conduit, means to conduct water from the spray chamber to the 25 flash vessel, and automatic means for controlling said valve to maintain a substantially constant air condition.

18. Air conditioning apparatus comprising 30 a spray chamber, means to supply air to and withdraw air from the spray chamber, a flash vessel, means to conduct water from the flash vessel to the spray chamber, a thermo-compressor connected to withdraw 35 vapor from the flash chamber, a condenser connected to receive vapor from the thermo-compressor, a by-pass conduit for conducting vapor from the discharge side of the thermo-compressor back to the inlet side 40 thereof, a valve in said by-pass conduit, means to conduct water from the spray chamber to the flash vessel, means to automatically control said valve in accordance with the condition of air in the spray chamber, and means for adjusting said valve.

19. The method of refrigeration which comprises introducing liquid into a closed vessel, withdrawing vapors of the liquid from the vessel to maintain a vacuum therein, 50 withdrawing liquid from the vessel, and introducing vapor into said vessel to regulate the degree of vacuum maintained therein.

20. The method of refrigeration which comprises introducing liquid into a closed 55 vessel, withdrawing vapors of the liquid from the vessel to maintain a vacuum therein, withdrawing liquid from the vessel, introducing vapor into said vessel to regulate the degree of vacuum maintained therein, 60 and controlling the volume or vapor introduced into said vessel.

21. Refrigerating apparatus comprising a flash chamber, means for introducing liquid into said flash chamber, means for withdrawing liquid from said flash chamber,

means for withdrawing vapors of said liquid from said flash chamber, means for introducing vapor into said flash chamber and means for controlling the amount of vapor so introduced into the flash chamber. 70

In testimony whereof, I hereunto affix my signature.

MEYER WEXLER.
